UNITED STATES PATENT OFFICE.

THOMAS S. BROWN, OF HEMET, CALIFORNIA.

STREET-LIGHTING DEVICE.

1,045,253.

Specification of Letters Patent. Patented Nov. 26, 1912.

Application filed March 2, 1912. Serial No. 681,202.

To all whom it may concern:

Be it known that I, THOMAS S. BROWN, a citizen of the United States, residing at Hemet, in the county of Riverside and State 5 of California, have invented certain new and useful Improvements in Street-Lighting Devices; and I do declare the following to be a full, clear, and exact description of the same, such as will enable others skilled in 10 the art to which it appertains to make and use the same, reference being had to the accompanying drawings, and the characters of reference marked thereon, which form a part of this application.

15 This invention relates to improvements in street lighting devices and particularly to electric lighting appliances, the object of the invention being to produce a lighting system in which the lights will be disposed 20 along the curbing of the streets in such a manner as to throw the light directly across the surface of the street and under all awnings, trees and other overhanging shadows, instead of on the tops of such trees, awnings, 25 roofs of buildings and like overhanging shadows as is the case with arc lamps or similar commonly used lighting apparatus.

30 A further object of the invention is to produce such a device as will be simple and inexpensive and yet exceedingly effective for the purposes for which it is designed.

These objects I accomplish by such structure and relative arrangement of parts as will fully appear by a perusal of the following specification and claim:

In the drawings similar characters of reference indicate corresponding parts in the several views.

Figure 1 is a front elevation of one of 40 my improved lighting members. Fig. 2 is a side elevation of the same. Fig. 3 is a sectional view taken on a line $x-x$ of Fig. 1. Fig. 4 is a side elevation of a modified form of the invention.

45 Referring now more particularly to the characters of reference on the drawings 1 designates a metallic base member having an upwardly projecting hollow hood 2, which hood is of a round, oval or balloon shape 50 and slightly elongated from front to back and provided with an opening 3 in its front side or the side directed toward the street.

The member 1 has suitable lugs 4 disposed preferably on its under side which 55 lugs are provided with slots 5 adapted to receive screws or bolts or slugs which may be

embedded in the cement of the curbing 6 to hold the base 1 and hood 2 stationary.

In the bottom of the base 1 and opening into the globe or hood 2 is a recess 7 provided with a suitable porcelain or other insulating base 8 secured to which is an upwardly projecting electric light socket 9 held in fixed position by means of suitable bedding of plaster of Paris or other suitable 60 material 10, the same being insulated from the member 1 by means of any suitable insulating material 11. Suitable wires 12 connected with the usual source of electrical energy 13 lead to the socket 9, in which 65 socket may be disposed an electric lamp 14.

The inside walls of the hood 2 may be painted white or lined with suitable reflecting material whereby the light from the lamp 14 will be thrown directly across the 70 surface of the street, which gives the light directly where it is wanted, while the hood 2 prevents it from being thrown across the sidewalk of the street. This feature of throwing the light directly across the street 75 surface aids the drivers of vehicles to see the street clearly and prevents the direct glare of the light from striking them in the eyes and blinding them. Also by placing the lights from twenty to forty feet apart on the 80 curbing the crossing of their light will entirely and effectually eliminate all shadows in streets, alleys, hallways and back of tree trunks, and in fact will perfectly illuminate 85 streets where the present known systems do 90 so imperfectly. If desired the front of the base 1 below the opening 3 may be sloped as shown at 15 so as to be perfectly illuminated and then a plate 16 secured thereto to receive a name, name of street or street 95 number as shown in Fig. 1. The device is safe-guarded from being injured by the wheels of wagons or other things by means of the backward slope of the hood 2 as shown or by means of a curving metallic 100 member 17 disposed on the curbing 6 in front of the base 1.

In the modified form shown in Fig. 4 the structure of the lamp holding hood is the same as shown in the other views but I further provide the opening 3^a of the hood 2^a with a strong heavy glass door or bull's-eye 18 which may be locked in position by means of a hasp or similar lock 19 to prevent anyone tampering with the light mechanism.

From the foregoing description it will

readily appear that I have produced such a device as substantially fulfills the objects of the invention as set forth herein.

While this specification sets forth in detail the present and preferred form of structure used in my invention, still in practice such deviations from such detail may be resorted to as do not form a departure from the spirit of the invention.

10 Having thus described my invention what I claim as new and useful and desire to secure by Letters Patent is:

A device of the character described, com-

prising the combination with the curb of a street, of a base member, lugs on said base member, means for securing said lugs in said curb, a hood on said base member, such hood having an opening, and a light disposed in said hood.

15 In testimony whereof I affix my signature 20 in presence of two witnesses.

THOMAS S. BROWN.

Witnesses:

C. A. MACK,
C. O. GILLETT.
